(57) **CLAIM**

The ornamental design for a thermostat back plate, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a front, right, top perspective view of a thermostat back plate according to a first embodiment of our new design;

FIG. 2 is a rear, right, top perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front, right, top perspective view of a thermostat back plate according to a second embodiment of our new design;

FIG. 10 is a rear, right, top perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof;

FIG. 16 is a bottom view thereof;

FIG. 17 is a front, left perspective view of a thermostat back plate according to a third embodiment of our new design;

FIG. 18 is a front view thereof;

FIG. 19 is a rear view thereof;

FIG. 20 is a right side view thereof;

FIG. 21 is a left side view thereof;

FIG. 22 is a top view thereof;

FIG. 23 is a bottom view thereof;

FIG. 24 is a front, left perspective view of a thermostat back plate according to a fourth embodiment of our new design;

FIG. 25 is a front view thereof;

FIG. 26 is a rear view thereof;

FIG. 27 is a right side view thereof;

FIG. 28 is a left side view thereof;

FIG. 29 is a top view thereof; and,

FIG. 30 is a bottom view thereof.

The broken lines in FIGS. 1, 3, 9-12, and 16 illustrate parts of the thermostat back plate that form no part of the claimed design.

(Continued)

The shading in the figures indicate the character and contour of the surfaces represented, not to be confused with surface ornamentation.
